UNITED STATES PATENT OFFICE.

JOHN B. BURDETT, OF CHICAGO, ILLINOIS, ASSIGNOR TO DAVIS-BOURNONVILLE COMPANY, OF NEW YORK, N. Y., AND CHICAGO, ILLINOIS, A CORPORATION OF NEW YORK.

ELECTROLYTIC CELL.

1,107,259.

Specification of Letters Patent. Patented Aug. 18, 1914.

Application filed November 8, 1912. Serial No. 729,752.

To all whom it may concern:

Be it known that I, JOHN B. BURDETT, a citizen of the United States, residing at Chicago, county of Cook, State of Illinois, have made a certain new and useful Invention 5 in Electrolytic Cells, of which the following is a specification.

This invention relates to electrolytic cells and particularly to such cells employed for 10 decomposing liquids into their composed gases.

The object of the invention is to provide 15 an electrolytic cell of the character referred to which is simple in construction and efficient in operation wherein the evolved gases are efficiently maintained in separation from each other and separately collected for use in the industries.

A further object of the invention is to 20 provide an electrolytic cell of the nature referred to wherein danger of dust, dirt, or other foreign substance collecting or flowing into the receptacle containing the solution to be decomposed is prevented.

25 Other objects of the invention will appear more fully hereinafter.

The invention consists substantially in the construction, combination, location and relative arrangement of parts, all as will be 30 more fully hereinafter set forth as shown in the accompanying drawing and finally pointed out in the appended claims.

Referring to the accompanying drawing: Figure 1 is a vertical central sectional view 35 on the line 1, 1 Fig. 2 of an electrolytic cell embodying the principles of my invention. Fig. 2 is a transverse horizontal sectional view of the same on the line 2, 2, Fig. 1, looking in the direction of the arrows. Fig. 40 3 is a view similar to Fig. 2 showing a modified arrangement embraced within the spirit and scope of my invention. Fig. 4 is a broken detail view showing one arrangement for applying the porous curtain 45 or diaphragm to separate the electrode plates of the cell. Figs. 5 and 6 are similar views showing modified arrangements for the same purpose.

In electrolytic cells employed for the 50 composition of liquids into their component gases as heretofore constructed, and particularly in the case of cells employed for the manufacture of commercial oxygen and hydrogen, electrode plates suitably separated 55 from each other and communicating with

70 bells or chambers for the collection of the gases therein have been suspended in open vats, tanks, or receptacles containing the electrolyte with the result that dust, dirt or other foreign substances collect or become deposited in the electrolyte thereby causing 65 an objectionable foaming and an interference with the proper electrolytic action, the foam being carried off along with the gas and causing irregularities which are undesirable. Such structures also usually embody complicated, numerous and extensive connections, piping and terminals which add to the expense of manufacture of the cells and the complications thereof.

70 It is among the special purposes of my present invention to avoid the complication of piping and other connections in apparatus of this nature and to prevent the deposit or accumulation of dust, dirt or other 75 foreign matter in the tank or receptacle containing the electrolyte and within which the electrolytic action is carried out.

In accordance with my invention, I propose to employ a vat, tank or receptacle to 80 contain the liquid to be decomposed and which is closed at its bottom and open at its top. I also propose to employ a top or cover for the open end of the receptacle and to form on the under surface of the top or 85 cover suitable chambers within which the electrode plates of one sign are suspended while the coöperating electrode plates of the other sign are suitably suspended in the vat or receptacle outside of said chambers, 90 and I propose to separate the electrode plates from each other by suitably suspended and supported porous diaphragms. And I propose to employ suitable delivery connections respectively communicating with the 95 closed chambers and with the open space outside of said chambers.

Referring to the accompanying drawing, 10 designates a vat, tank or other suitable receptacle adapted to contain the caustic 100 solution or other liquid to be decomposed. The particular form shown, to which, however, my invention is not to be limited or restricted, is generally of rectangular shape, closed at the bottom and open at the top. Applied to the top or open end of the receptacle 10 is a top or cover 11, which is provided with a plurality of chambers 12, formed by walls 13, preferably formed integral with the top 11 and depending from 110

the under surface thereof. The chambers 12 thus formed extend lengthwise of the top or cover and preferably in parallel relation to each other and are open at their lower edges, opening freely into vat or tank 10. In use the lower edges of the chambers 12 dip into or are immersed in the liquid electrolyte contained in the tank 10. In practice the various chambers 12 should be in communication with each other. In the particular form shown as exemplifying my invention, a duct or passage 14 is provided through the body of the top or cover and forming a communication between said chambers. Suitably suspended through and within the open lower mouth or edge of each chamber 12 is an electrode sheet or plate 15. A convenient arrangement for suspending the electrode plates 15 is shown wherein rods 16 extend through the top or cover 11 and are welded or otherwise secured to the upper edges of the electrode plates 15. These rods not only serve to support the electrode plates but they also serve as circuit terminals for said plates. Intermediate adjacent chambers 12 and in the space within the receptacle outside of said chambers are suitably suspended and supported the coöperating electrode plates 17 having similar suspending rods 18 passing through the top or cover 11. Of course the rods 16, 18 should be efficiently insulated from the top or cover 11 as indicated at 40, Fig. 1. The electrode plates 15, 17 depend down into the electrolyte contained in the tank 10. In order to prevent intermingling of the gases evolved from the surfaces of electrode plates 15, 17 within the tank 10, said plates are separated from each other by interposed porous diaphragms or curtains of suitable material, such, for instance, as asbestos; as indicated at 19. These curtains may be supported within the tank 10 in any suitable or convenient manner or in such relation to the electrode plates 15, 17 as to efficiently separate the same from each other. A convenient arrangement is shown wherein the porous diaphragms 19 are suspended from the exterior surface of the lower edges of the walls 13 of chambers 12.

In Fig. 3 a slightly modified arrangement is shown wherein the tank 10 is divided into two distinct and separate chambers 20, 21 by a wall 22, bent back and forth upon itself into parallel portions, said wall, in accordance with my invention being formed integrally with the top or cover for the tank and depending from the under side thereof downwardly into the tank and immersed at its lower edge in the electrolyte. The electrodes 23, 24 are suspended between the adjacent folds or parallel portions of the wall 22 on opposite sides of said wall, that is, respectively, within the chambers 20, 21, said plates being suspended in the manner above

described, with reference to the plates 15, 17 of the arrangement shown in Figs. 1 and 2. It will be understood that the electrode plates 15, 17 are connected to terminals of opposite sign in a supply circuit for a current of electricity. Similarly, electrode plates 23, 24 of the arrangement shown in Fig. 3 are connected to terminals of opposite sign. In the case of the arrangement shown in Figs. 1 and 2, the gas evolved from plates 15 collects in the chambers 12, which are in communication with each other, and from these chambers the collected gas passes off through any suitable delivery connections such, for instance, as the lantern 27 and thence to a suitable gasometer and service pipes in a well known manner. In like manner the gas evolved from electrode plates 17 collect in the top of the tank 10 in the space outside of said chambers 12 from which said gas is delivered in the ordinary or usual manner, as, for instance, through the lantern 27 and thence to the gasometer, receiving tank or service pipes in the usual way. Similarly in the arrangement shown in Fig. 3 the gas evolved at the surface of electrode plates 23 collect in chamber 21 and is delivered therefrom through pipe connection 28 while the gas evolved at the surface of plates 24 collect in chamber 20 and pass off through connection indicated at 29.

Where the walls 13 or 22 are curved it may be inconvenient to apply porous diaphragm 19 to the inner arcs of the curve of said walls. In order to overcome this obstacle various expedients may be employed as shown, for instance, in the arrangement shown in Figs. 4 and 5, the curtain 19 may be slitted as indicated at 30 so as to slip edgewise over the lower edge of the wall 13 so that the diaphragm may be applied to the exterior surface of the wall 13 at the bend thereof. This form of connection is also particularly applicable to the construction shown in Fig. 3, as clearly indicated therein. Another arrangement is shown in Fig. 6, wherein the curtain 19 is made in sections placed respectively on the outside and inside surface of the wall 22, for instance, so as to be applied only to the convexed surface thereof, the adjacent edges of the sections of curtain passing somewhat beyond each other and secured by clamp bolts and plates indicated at 31 applied thereto.

It will be understood that in the construction shown in Figs. 1 and 2 as many chambers, 12, may be employed for each tank 10 as may be desired, according to the desired capacity or output thereof. While, therefore, I have shown only two of such chambers, my invention is not to be limited or restricted in this respect.

From the foregoing description it will be seen that I provide an exceedingly simple, inexpensive and efficient electrolytic cell

wherein I am enabled to do away with extensive and complicated pipe connections and fittings, wherein the cell tank is maintained closed by a top or cover applied thereto, wherein the electrode plates are maintained in efficient separation from each other and wherein intermingling of the evolved gases is prevented.

Having now set forth the objects and nature of my invention and a construction embodying the principles thereof, what I claim as new and useful, and of my own invention, and desire to secure by Letters Patent is:—

1. In an electrolytic cell, a tank, a top or cover for closing the same, said top or cover having integral wall portions depending from the bottom surface thereof into the tank and forming separated chambers, means extending through said top or cover and into said chambers, electrode plates respectively supported by said means, coöperating electrode plates arranged in the tank, means also extending through said top or cover for supporting said coöperating electrode plates, a porous diaphragm separating said electrode plates and gas delivery connections communicating respectively with said chambers and tank.
2. In an electrolytic cell, a tank, a cover therefor having walls depending from the bottom surface thereof forming a plurality of separated chambers, means to form a communication between said chambers, electrode plates suspended from within said chambers, coöperating electrode plates suspended within said tank, porous diaphragms separating said plates and gas delivery connections communicating respectively with said chambers and tank.

3. In an electrolytic cell, a tank having a top or cover, integral walls formed with said top or cover and forming separated chambers, said chambers depending from the bottoms of the top or cover into the tank and communicating with each other, supporting rods passing through said top or cover, electrode plates respectively arranged in juxtaposition to each other in said chambers and in said tank and supported by said rods porous diaphragms separating said plates and gas delivery connections communicating respectively with said chambers and tank.

4. In an electrolytic cell, a tank, a cover therefor, said cover having integral walls depending from the bottom surface thereof and forming a plurality of separated chambers, said walls dipping into the electrolyte within the tank, a passage formed in the cover to open communication between said chambers, electrode plates, means extending through the cover and into said chambers for supporting said plates, coöperating electrode plates, means also extending through the cover for suspending said coöperating electrode plates in the tank, porous diaphragms separating said plates and gas delivery connections communicating respectively with said chambers and said tank.

In testimony whereof I have hereunto set my hand in the presence of the subscribing witnesses, on this first day of November A. D. 1912.

JOHN B. BURDETT.
